UNITED STATES PATENT OFFICE.

EDUARD SALZER, OF LA PORTE, INDIANA.

VALVE-GEAR.

SPECIFICATION forming part of Letters Patent No. 541,291, dated June 18, 1895.

Application filed June 1, 1894. Serial No. 513,206. (No model.)

To all whom it may concern:

Be it known that I, EDUARD SALZER, a citizen of the United States, residing in La Porte, in the county of La Porte and State of Indiana, have invented a new and useful Improvement 5 in Valve-Gear for Steam-Engines, of which the following is a specification.

This invention relates to a compact, cheap and simple device applied to the crank shaft 10 of a reciprocating steam engine and connected to the valve operating eccentric for changing the throw of the eccentric to reverse the operation of the valves.

The nature of the improvement will be fully 15 understood from the subjoined description and the accompanying drawings, in which—

Figure 1 is a diagrammatic plan view of a steam-engine provided with my invention. Fig. 2 is a side elevation of the reversing apparatus. This and the following figures are 20 on a larger scale than Fig. 1. Fig. 3 is a section on the line 3 3 of Fig. 2, looking in the direction to which the arrow points. Fig. 4 is a side view similar to Fig. 2, but showing 25 the reversing-gear in a different position with the throw of the eccentric reversed. Fig. 5 is a section on the line 5 5 of Fig. 4, looking in the direction to which the arrow points. Fig. 6 is a longitudinal vertical section taken on 30 the line 6 6, indicated in Fig. 5.

Like letters of reference indicate like parts throughout all the figures.

In said drawings A is the crank shaft. B is the valve operating eccentric which is 35 loosely mounted on the shaft. Rigidly connected to the eccentric or made one therewith is the stop plate B' having the segmental stop projection B². Adjacent to this stop plate and keyed to the shaft A is the opposing stop 40 plate C which is perforated with the circular slot c. A projection b from the stop plate B' passes through this slot and is secured to the face plate B³, which face plate carries the projecting arm B⁴. It will be seen that the eccentric B, the stop plate B', the stop B², the face plate B³ and the projection B⁴ are all 45 rigidly connected together. The face plate B³ and projection B⁴ may be readily and quickly detached.

50 b' is a bolt connecting the projection B⁴ and face plate B³.

D is a hollow sleeve fitted at one end with

a grooved collar E to receive the forks of a reversing lever e. Shown in Fig. 1. The sleeve D is splined or keyed to the shaft A by the 55 spline a in such manner that said sleeve will revolve with the shaft A but may be moved longitudinally thereon. To afford a better bearing for the sleeve I prefer to extend from the stop C a tubular projection C' which extends into the sleeve D, enlarges the driving shaft A and affords a ready means of fixing the stop plate C rigidly to said shaft.

In the sleeve D is cut a spiral slot or groove D'. I prefer to cut this slot entirely through 60 the sleeve in order to facilitate lubrication. Entering this slot from the projection B⁴ is a pin d. When the apparatus is in the position indicated at Fig. 2, the sleeve D may be moved by the reversing lever e engaging the collar 65 E into the position indicated at Fig. 4 while the shaft A is revolving and the engine in motion. The effect of thus moving the sleeve will be to reverse the position of the eccentric; that is to say, the spiral slot D' by 70 engaging the pin d, will carry the projection B⁴ around with a rotary movement; and the projection B⁴ will impart to the face plate B³, the stop plate B' and the eccentric B the same 75 rotary advance, which rotary advance will be checked or stopped by reason of the stop B² coming into contact with the stop B⁵, the latter on the plate C. The effect of reversing the position of the eccentric, moving it from one to the other side of the shaft is, as will be 80 understood, to reverse the throw of the eccentric and the position of the valves and consequently reverse the motion of the engine.

It will be noticed that the construction of 85 this reversing apparatus is exceedingly simple. It is compact; easily lubricated at all parts; can be readily applied to reciprocating engines of almost every form; puts no strain upon the engine; and is exceedingly strong and durable.

I claim—

1. The reversible valve gear for reciprocating steam engines, comprising in combination 90 the crank shaft A, the eccentric B loosely mounted on said shaft, stop plate B' rigidly connected to the eccentric, the stop plate C keyed to the shaft, the projection B², the face plate B³ connected to the stop plate B', the arm B⁴ projecting from the face plate B³, the

hollow sliding sleeve D splined to the shaft and having the spiral slot D', the pin d and means for sliding the sleeve, substantially as specified.

- 5 2. The valve reversing gear for reciprocating steam engines comprising in combination an eccentric loosely mounted on the crank shaft, a face plate secured rigidly to the eccentric, a projection extending from the face
10 plate longitudinal with the shaft and carrying a pin, a hollow sleeve splined to the shaft

and provided with a spiral slot into which the pin enters, said spirally grooved sliding sleeve being arranged between the pin carrying the projection and the shaft, and means for sliding the sleeve to reverse the throw of the valve, substantially as specified. 15

EDUARD SALZER.
